FIG. IV

UNITED STATES PATENT OFFICE

2,327,582

THERMOSTATIC CONTROL

Robert J. Dougherty, Ambler, Pa., assignor to
 John Wood Manufacturing Company, Inc.,
 Philadelphia, Pa., a corporation of Delaware

Application May 18, 1942, Serial No. 443,360

4 Claims. (Cl. 236—21)

My invention relates to devices for controlling the supply of gas to the burner of an automatic gas-fired water heater, wherein the burner is provided with a pilot which normally remains lighted continually during the operation of the heater, regardless of whether the burner is "on" or "off." It is customary to control the temperature of the water in such heaters by a suitable thermostat, located in the water compartment, which effects an automatic shutting off of the supply of gas to the main burner when the water in the heater reaches a predetermined temperature. The action of the thermostatic control also restores a flow of gas to the main burner when the temperature of the water in the water compartment falls below the temperature for which the thermostat is set.

It is also usual practice to include in such water heaters a safety shut-off device to automatically shut off the main gas supply to the burner should the pilot become extinguished for any cause.

Accordingly, in heaters of the prior art, two sets of valves and valve casings ordinarily have been provided, the operation of one of which is effected by the thermostat located in the water compartment, and the operation of the other is effected by the safety shut-off device. In order that these valves be operated safely, it is essential that both of them be absolutely tight when closed and that each be designed for a maximum of opening when in open position. Furthermore, it is essential that the gas passages be of such dimension that a minimum drop in pressure of the gas results. Pressure drop may result from constricted passageways or such changes in direction of the gas which causes turbulence, or an eddying effect.

Although some prior art structures have utilized a single casing for both the thermostat and safety shut-off, in all such structures separate valves are used for the performing of each function.

The principal feature of my invention is the combining of the prior art separate thermostat and safety shut-off devices in a single device in which only one valve and body are required to perform the dual functions which heretofore necessitated the use of two separate sets of valves, etc.

Another feature of my invention is to provide a device in which there is a material reduction of pressure drop, which inherently exists when two separate valves and parts are used.

Another feature of my invention is the providing of a device in which valve adjustment is minimized because but one valve is used.

Another feature of my invention is the providing of a device which may be readily and facilely adapted to be tight when closed.

Another feature of my invention is the provid-

ing of a device in which the total number of parts and the cost thereof is materially reduced.

Another feature of my invention is the providing of a device which is less liable to stick than an ordinary shut-off valve by reason of the fact that in my device the valve is constantly operating, whereas the safety shut-off valve of the prior art closes only in an emergency.

Another feature of my invention is that its use permits the appearance of the assembled water heater to be enhanced by reason of the fact that fewer accessories are visible on the outside of the heater casing than when the multiplicity of prior art devices required to perform the same functions are used.

My invention includes the various novel features of construction, arrangement, and method of operation hereinafter more definitely specified.

Fig. I is a fragmentary vertical sectional view of an automatic gas water heater embodying my invention. In Fig. I the thermostatic elements are shown in the position which they assume when the pilot is lighted, the main thermostat in "off" position, and the valve controlling the main gas supply to the burner closed.

Fig. II is a fragmentary view of the structure shown in Fig. I, but in which the elements are shown in a position in which the pilot is lighted, the main thermostat in "on" position, and the gas valve open.

Fig. III is a view similar to Fig. II, but in which the elements are shown in the position which they assume when the pilot is extinguished, the main thermostat in "on" position, and the gas valve in closed position.

Fig. IV is a fragmentary vertical sectional view of an automatic gas water heater embodying a modified form of my invention, and in which the thermostatic elements are shown in the position which they assume when the pilot is lighted, the main thermostat in "off" position, and the gas valve closed.

Fig. V is a fragmentary sectional view of the structure shown in Fig. IV, but in which the elements are shown in the positions which they assume when the pilot burner is lighted, the main burner is in "on" position, and the gas valve open.

Fig. VI is a fragmentary vertical sectional view of another modification of the devices shown in Figs. I to III and Figs. IV and V, and with the thermostatic elements thereof shown in the position which they assume when the pilot is lighted, the main thermostat in "on" position, and the gas valve open.

Referring to Fig. I; I have shown a fragment of an automatic water heater in which my invention is embodied, including the cylindrical shell 1 of the water compartment which is provided with a bottom closure 2. The bottom clo-

sure 2 separates the water compartment 1 from the combustion chamber 3 in which is located the main gas burner 4 of a conventional type, the right hand end only of which is shown in Fig. I. Gas is supplied to the burner 4 through the pipe 6, connected to a suitable source of gas supply. I have found it desirable to include in the gas line the gas valve 7 by which the gas supply to the burner may be shut off manually when it is desired to permanently shut off the heater. Said valve 7 has the gas passageway 8 therethrough under control of the valve plug 9 which is provided with the opening 10 therethrough. In the position shown in Fig. I, said valve 7 is in open position.

Referring to Figs. I, II, and III; the valve casing 12 has the screw threaded opening 13 for engagement with the screw threaded end 14 of the valve 7. Said valve casing 12 has the gas inlet 15 and outlet 16 upon opposite sides of the partition 17. Said partition 17 has valve ports 18 through it, controlled by the valve 20 which has an inner stem 21 mounted to reciprocate in the bearing 22 formed in said partition 17. Said valve 20 is continually pressed toward its valve seat 24 by a light spring 25 which bears at its inner end upon the valve 20 and abuts at its outer end against the closure cap 26 which is detachably engaged with said casing 12 in any convenient manner.

Said stem 21 is provided at its inner end, in screw threaded relation therewith, with the axial adjusting screw 27 to facilitate axial adjustment of said screw in cooperative relation with the resilient tripod spring 30 of the clicker 31 by which said valve 20 is snapped open in opposition to the pressure of the spring 25, as hereinafter described. Said clicker 31 is of the well known type used in thermostatically operative valves, for example, the thermostatically operative valve disclosed in Letters Patent No. 1,974,646 granted to me September 25, 1934. The spring 30 is made of concavo-convex form with its convex surface normally presented toward the circular thrust disk 32 which is positioned in the annular offset recess 34 formed in the casing 12.

Said casing 12 has the cover element 36 which is detachably rigidly connected to said casing. Said cover element 36 is provided with a conical recess 37 in which the conical thrust block 38 is positioned with freedom of movement, and the base of the cone is in sliding engagement with the top surface of the clicker element 31. The top closure 36 is provided with a screw threaded opening 40 in which is engaged a screw threaded nut 41 carrying the thermostatic element 42. The thermostatic element 42 is conveniently of the liquid filled type comprising the tube 43 which is filled with a liquid 44 having a greater coefficient of expansion than the tube 43. The left hand end portion of said tube 43 extends into the water in the water compartment 1 of the heater. The liquid 44 is maintained in filled fluid tight relation within the tube 43 by means of the Sylphon bellows 46 which is rigidly fastened only at its lower end in the annular recess 47 formed in the nut 41. The upper free end of the bellows 46 carries the plunger 50, the lower end of which is mounted with freedom of reciprocatory movement in the bearing 51 formed in the cover 36. The lower end of the plunger 50 is adapted for engagement with the cone block 38 to effect movement of the snap spring 30 and valve 20, as hereinafter described.

The outlet 16 of the valve casing 12 has the screw threaded opening 55 for engagement with the screw threaded end 56 of the needle valve fitting 57 which is in engagement with the right hand mixing tube end of the main burner 4. Said fitting 57 is provided with the gas passageway 58 which affords communication between the valve casing outlet 16 and the main burner 4. The burner 4 is provided with the orifice 60 under control of the manually adjustable needle valve 61. The right hand end of the needle valve 61 is in screw threaded engagement with a screw threaded opening 62 formed in the fitting 57. I have found it convenient to provide the screw threaded end of said needle valve 61 with the screw driver slot 63 to facilitate adjustment of said valve. I also have found it desirable to protect the needle valve 61 from accidental displacement by providing the screw plug 64 for closure of the screw threaded opening 62.

The safety shut-off device includes the thermostatic couple comprising the outer tube 65 formed from material which is expansionable under the influence of heat from the pilot. The right hand end of said tube 65 is conveniently in screw threaded engagement with the screw threaded opening 66 formed in the cover 36 of the valve casing 12. The other element of the thermostatic couple is the inner rod 67 which is formed from material having a negligible coefficient of expansion. The left hand end of said non-expansionable rod 67 is rigidly mounted in the plug 68 which is in integral relation with the left hand end of the tube 65. The right hand end 35 portion of said rod 67 is mounted with freedom of reciprocatory movement in the bearing 69 formed in the valve casing cover 36. The right hand end of said rod 67 is adapted for engagement with the cone block 38 to effect movement thereof, as hereinafter described.

Heat is normally applied to the left hand end of the tube 65 of the shutoff device by means of the flame from the lighted pilot burner 70, which is positioned beneath the tube 65 and also so positioned with respect to the main burner 4 as to cause said main burner 4 to become lighted when gas flows thereto. The pilot burner includes the gas tube 71 which is conveniently in screw threaded engagement with the fitting 72 in communication with the gas supply line at some point in the gas line in which the supply of gas thereto would not be affected by the manually operative shut-off valve 7. As shown in Fig. I, I have found it convenient to connect said fitting 72 in communication with the upper end of the gas passageway 8 of the valve fitting 7. Said fitting 72 is provided with the manually operative valve 73 by which the gas supply to the pilot may be shut off when it is desired to shut down the heater permanently and place it in inoperative condition.

Figs. IV and V show a modified form of my invention in which a system of levers is utilized to effect movement of the clicker element which controls the operation of the valve.

Referring to Fig. IV, I have shown a fragment of an automatic water heater in which my modified form of invention is embodied, including the cylindrical shell 101 provided with the bottom closure 102. The bottom closure 102 separates the compartment 101 from the combustion chamber 103 in which is located the main gas burner 104 of a conventional type, only the right hand end of which is shown in Fig. IV. Gas is supplied to the burner 104 through the pipe 106

connected to a suitable source of supply. I have found it desirable to include in the gas line the gas valve 107, similar to the gas valve 7, which is provided with the gas passageway 108 and valve plug 109 with the opening 110 therethrough. The valve 107 is shown in open position in Fig. IV.

Referring to Figs. IV and V, the valve casing 112, similar to the casing 12 shown in Figs. I, II and III, has the screw threaded opening 113 for engagement with the screw threaded opening 114 of the valve 107. Said casing 112 has the gas inlet 115 and outlet 116 upon opposite sides of the partition 117. Said partition 117 has valve ports 118 through it, controlled by the valve 120 which has an inner stem 121 mounted to reciprocate in the bearing 122 formed in said partition 117. Said valve 120 is continually pressed toward its valve seat 124 by the light spring 125 which bears at its inner end against the valve 120 and abuts at its outer end against the closure cap 126 which is detachably engaged with said casing 112 in any convenient manner.

Said stem 121 is provided at its inner end with the axial adjusting screw 127 to facilitate axial adjustment of said screw in cooperative relation with the resilient tripod spring 130 of the clicker 131 by which said valve 120 is snapped open in opposition to the pressure of the spring 125, as hereinafter described. Said clicker 131 is similar to the clicker 31 shown in Figs. I, II, and III and heretofore referred to. The spring 130 has its convex surface normally presented toward the circular thrust disk 132 which is positioned in the annular offset 134 formed in the casing 112.

Said casing 112 has the cover element 136 which is detachably rigidly connected to said casing. The closure 136 is provided with the screw threaded opening 140 in which is engaged the nut 141 carrying the thermostatic element 142. The thermostatic element 142, similar to the thermostatic element 42, comprises the tube 143 filled with a liquid 144 having a greater coefficient of expansion than the tube 143. The left hand end portion of the tube 143 extends into the water in the water compartment 101 of the heater. The liquid 144 is maintained in filled fluid tight relation within the tube 143 by means of the Sylphon bellows 146 rigidly fastened at its right hand end in the annular recess 147 formed in the nut 141. The left free end of the bellows 146 carries the plunger 150, the right hand end of which is mounted with freedom of reciprocatory movement in the bearing 151 formed in the cover 136.

The outlet 116 of the valve casing 112 has the screw threaded opening 155 for engagement with the screw threaded end 156 of the needle valve fitting 157 which is in engagement with the right hand mixing tube end of the main burner 104. Said fitting 157 is provided with the L-shaped gas passageway 158 which affords communication between the outlet 116 and the main burner 104. Said burner 104 is provided with the orifice 160 under control of the manually adjustable needle valve 161. The right hand end of the needle valve 161 is in screw threaded engagement with a screw threaded opening 162 formed in the fitting 157. The screw threaded end of the needle valve has the screw driver slot 163 to permit said valve to be adjusted. The needle valve 161 is protected from accidental displacement by providing the screw plug 164 for closure of the opening 162.

The safety shut-off device shown in Fig. IV is similar to that shown in Fig. I and includes the

thermostatic couple comprising the outer tube 165, the right hand end of which is conveniently in screw threaded engagement with the screw threaded opening 166 formed in the cover 136. The other element of the thermostatic couple is the inner rod 167 which is formed from material having a negligible coefficient of expansion. The left hand end of said rod 167 is rigidly mounted in the plug 168 in integral relation with the left hand end of the tube 165. The right hand end of said rod 167 is mounted with freedom of reciprocatory movement in the bearing 169 formed in the casing cover 136.

Heat is normally applied to the left hand end of the tube 165 by a flame from the lighted pilot burner 170 positioned beneath the tube 165 and also so positioned with respect to the main burner 104 as to cause said main burner 104 to become lighted when the gas flows thereto. The pilot burner includes the tube 171 conveniently in screw threaded engagement with the fitting 172 in communication with the gas supply line at some point not affected by the manually operative shut-off valve 107. As shown in Fig. IV, the fitting 172 is in communication with the upper end of the gas passageway 108 of the valve fitting 107. Said fitting 172 is provided with the manually operative valve 173.

As shown in Figs. IV and V, movement of the clicker 131 is effected by means of the levers 175 and 176 which are pivotally fulcrumed respectively at 177 and 178 upon their respective ball tipped adjustable screw studs 180 and 181. The studs 180 and 181 are made adjustable to facilitate the preliminary setting of the device, after which said fulcrums 177 and 178 remain fixed. The screw stud 180 is conveniently adjustable by means of the lever 182, connected to the shank of the screw stud 180, which extends through the stuffing box 183, as shown in Fig. IV. The screw stud 181 is conveniently provided with the screw driver slot 185 in alignment with the screw threaded opening 186 formed in the casing 112. Said opening 186 is provided with the screw threaded closure plug 187.

Said levers 175 and 176 conveniently are formed as levers of the second order, and are arranged so that their respective power ends 190 and 191 may exert force upon the clicker 131, approximately at its axis. As shown in Figs. IV and V, the power end 190 of the lever 175 overlies the power end 191 of the lever 176, and the power end 191 of the lever 176 engages the outer surface of the clicker element 131. The right hand end of the plunger 150 is adapted for engagement with the lever 175 at a point between its fulcrum and power end; and the right hand end of the rod 167 is adapted for engagement with the lever 176 at a point between its fulcrum and power end to effect movement of the snap spring 130 and valve 120, as hereinafter described.

I have shown in Fig. VI a modification of the structure shown in Figs. IV and V. In Fig. VI a single lever 275 is utilized, and its power end engages the outer surface of the clicker element 231, similar to said clicker 131, to effect movement of the snap spring 230 and valve 220, as herein-after described. Said lever 275 is fulcrumed at 277 upon the ball tipped adjustable screw stud 280. Said stud 280 is made adjustable to facilitate the preliminary setting of the device, after which said fulcrum 277 remains fixed. Said lever 275 is conveniently formed as a lever of the second order and is arranged so that its power

end 290 may exert force upon the clicker 231, approximately at its axis.

The casing 212 of the form of my invention shown in Fig. VI has the cover element 236 which is detachably rigidly connected to said casing by any convenient means. The closure 236 is provided with the screw threaded opening 240 in which is engaged a nut carrying a thermostatic element similar to the elements 42 and 142. In Fig. VI there is shown only a fragment of the plunger 250, similar to the plungers 50 and 150, the right hand end of which is mounted with freedom of reciprocatory movement in the bearing 269 formed in the cover 236.

The closure 236 is provided with the screw threaded opening 266 for engagement with the screw threaded end of the tube, similar to the tubes 65 and 165, of a thermostatic couple safety shut-off device. In Fig. VI there is shown only a fragment of the inner rod 267, the other element of the thermostatic couple, which is formed from material having a negligible coefficient of expansion. The left hand end of said rod 267 is mounted in a plug in integral relation with the left hand end of said tube, in the same manner as is shown in Figs. I and IV. The right hand end of said rod 267 is mounted with freedom of reciprocatory movement in the bearing 269 formed in the casing cover 236. It is to be understood that a pilot, similar to the pilots 70 and 170, is included in the form of my device shown in Fig. VI.

In the form of my invention shown in Fig. VI, the safety shut-off tube and rod 267 are mounted concentric and in a straight line with the clicker 231 and valve 220.

The right hand end of the plunger 250 is adapted for engagement with the lever 275 at a point between its fulcrum and power end and the right hand end of the rod 267 is adapted for engagement with the power end 290 of said lever 275 to effect movement of the snap spring 230 and valve 220, as hereinafter described.

Operation

The form of my invention shown in Figs. I, II, and III operates as follows:

With the heater shut off with both the main burner and pilot extinguished by a manual closing of the hand valve 7 and valve 73 controlling the pilot, and with the water in the water compartment 1 cold and below the temperature for which the thermostatic element is set, the various elements within the casing 12 assume the positions shown in Fig. III. In such position, the liquid 44 within the tube 43 has contracted, which has permitted the Sylphon bellows 46 to expand and raise the plunger 50 upwardly and out of engagement with the conical thrust block 38, as is shown in Fig. III. However, with the pilot 70 extinguished, the tube 65 of the safety shut-off thermostatic couple has contracted, which has caused the non-expansionable rod member 67 to be moved to the right in its bearing 69 to come into engagement with the conical thrust block 38 to exert pressure on the cone, forcing it along the side of the conical recess 37 at A with a resultant movement of the cone in the direction of the arrow in Fig. III. Movement of the conical thrust block in the direction of the arrow in Fig. III exerts forces upon the clicker 31 which causes the tripod spring 30 thereof to be forced against the circular thrust disk 32, thereby causing the clicker spring 30 to snap inward, or to concave position, to permit

the valve 20 to be closed under the action of its light spring 25.

To initiate the cycle of operation, the operator first opens the valve 7 which controls the gas 5 from a suitable supply line. The operator then opens the pilot valve 73 to the position shown in Fig. I and the pilot 70 is lighted. The heat therefrom is applied to the tube 65 which causes said tube 65 to expand and move to the left to 10 the position in which it is shown in Fig. I. Such expansion of the tube 65 carries with it the non-expansionable rod member 67 and causes said rod 67 to move away from the cone 38 and to the position shown in Fig. I.

With the clicker 31 relieved from pressure, it 15 moves from the position shown in Fig. III to the position shown in Fig. II, thereby permitting the spring 30 to snap to convex position to open the valve 20, against the effective forces of its light spring 25. With the valve 20 in open position, 20 gas flows through the pipe 6, passageway 8 in the opened valve 7, casing inlet 15, around the valve 20, and through the valve ports 18 to the casing outlet 16, through the passageway 58 in the fitting 57, through the burner orifice 60, and 25 to the main burner 4 where the gas is ignited by the flame of the pilot 70 which is in close proximity to said burner 4.

As the water in the container 1 reaches the 30 temperature for which the water thermostat is set, the liquid 44 in the tube expands and causes the plunger 50 to move downwardly in its bearing 51 and into engagement with the conical thrust block 38 and moves said conical thrust block until it rests against the wall B of the conical recess 37. Continued pressure by the plunger 50 upon the cone 38 causes resultant movement of said conical thrust block 38 in the direction of the arrow shown thereon in Fig. I, 40 causing the clicker spring 30 to snap to its concave position which permits said valve 20 to be moved to closed position under the effective forces of its light spring 25, as shown in Fig. I.

When water is withdrawn from the heater to a 45 sufficient amount to cause the temperature of the water in the container 1 to fall below that for which the thermostat is adjusted, the liquid 44 in the tube 43 cools and contracts, thereby permitting the plunger 50 to be moved upwardly by 50 expansion of the Sylphon bellows 46 which results in the pressure on the clicker 31 being released, thereby permitting the spring 30 to snap to convex position, and the valve again is opened and the various elements again assume the valve open 55 position shown in Fig. II.

Should the pilot become extinguished for any 60 reason, the tube 65 cools and contracts, thereby moving the non-expansionable rod 67 into pressure exerting engagement with the cone 38, which causes said cone to slide along the face A of the conical recess 37 and exert pressure on the clicker 31 in the direction of the arrow in Fig. III, to cause the spring 30 to snap to concave position and the valve 20 to be closed under the effective forces of its light spring 25. As is well understood 65 in the art, the forces exerted by the clicker spring when free to snap outward to convex position, are many times greater than the effective forces of the light valve spring 25.

70 Referring to the form of my invention shown in Figs. IV and V; the same valve opening and valve closing effects are effected by the use of a system of levers operating on the clicker 131 and affected by the safety shut-off and water thermostat. Referring to Figs. IV and V, with the

pilot lighted, the safety shut-off rod 167 moves, in the direction of the arrow marked thereon, from the position indicated in dotted lines in Fig. IV to the position shown in full lines. Thus, when the pilot is lighted, the valve 120 is under control of the lever 175 acted upon by the plunger 150 of the water thermostat, as the lever 176 is free to float idly between its mechanical limits.

Assuming that the water in the container 101 is below that for which the thermostat is set, the liquid 144 within the tube 143 has contracted, which has permitted the Sylphon bellows 146 to expand and move the plunger 150 to the left in Fig. V and out of pressure engagement with the lever 175. When the clicker 131 is thus relieved from pressure, it moves from the position shown in Fig. IV to the position shown in Fig. V, thereby permitting the spring 130 to snap to convex position and open the valve 120 against the effective forces of its light spring 125. With the valve 120 in open position, gas flows around the valve 120 and through the valve ports 118 to the main burner 104 where the gas is ignited by the flame of the pilot 170, in the same manner as heretofore described with reference to the form of my invention shown in Figs. I, II, and III.

As the water in the container 101 reaches the temperature for which the water thermostat is set, the liquid 144 in the tube 143 expands and causes the plunger 150 to move to the right, as shown in Fig. IV, in its bearing 151. Continued pressure by the plunger 150 upon the lever 175 causes the power end 190 of the lever 175 to exert pressure on the clicker 131, thereby causing the clicker spring 130 to be forced against its thrust disk 132, which causes the clicker spring 130 to snap to its concave position shown in Fig. IV, which permits said valve 120 to be moved to closed position under the effective forces of its light spring 125.

When water is withdrawn from the heater to a sufficient degree to cause the temperature of the water in the container 101 to fall below that for which the thermostat is adjusted, the liquid 144 in the tube 143 cools and contracts, thereby permitting the plunger 150 to be moved to the left by expansion of the Sylphon bellows 146 which results in the pressure on the clicker 131 being released, thereby permitting the spring 130 to snap to convex position, and the valve 120 again opens and the various elements again assume the valve open position shown in Fig. V.

Should the pilot become extinguished for any reason, the tube 165 cools and contracts, thereby moving the non-expansionable rod 167 to the right into pressure exerting engagement with the lever 176 which causes said lever to exert pressure on the clicker 131 to cause the spring 130 to snap to concave position and the valve 120 to be closed under the effective forces of its light spring 125.

Referring to the form of my invention shown in Fig. VI, the same valve opening and valve closing effects are effected by the use of but a single lever 275 operating on the clicker 231. In the form shown in Fig. VI, the safety shut-off tube and non-expansionable rod member 267 are mounted concentric and in a straight line with the clicker 231 and valve 220, to thereby act directly on such parts and to eliminate the necessity of a lever, such as the lever 176 of the form

of my invention shown in Figs. IV and V. The lever 275 bears directly against the clicker 231 and the rod 267 is positioned for engagement directly on the power end 290 of the lever 275. In the form of my invention shown in Fig. VI, when the pilot is lighted expansion of the tube draws the end of the rod 267 away from the power end 290 of the lever 275, and said rod 267 thereafter does not interfere with the thermostatic action as long as the pilot remains lighted. Except for the fact that the power end 290 of the lever 275 bears directly against the clicker 231, the form of my device shown in Fig. VI functions in the same manner in response to movements of the thermostatic plunger 250 as has been heretofore described with reference to the form of my invention shown in Figs. IV and V.

It is obvious that many variations of lever arrangement are possible and, accordingly, I do not desire to limit myself to the precise details of construction, arrangement, and method of operation herein set forth, as it is obvious that various modifications may be made therein without departing from the essential features of my invention, as defined in the appended claims.

I claim:

1. In a thermostatically operative valve structure; the combination with thermostatic means responsive to the water temperature in the container of a water heater; of safety shut-off thermostatic means for the gas burner of said water heater; a valve casing having a gas inlet and a gas outlet with a valve port between them; a single valve responsive to both said water thermostat and said safety shut-off thermostatic means for controlling said valve port; means for effecting snap action of said valve; and a conical block in operating relation to both of said thermostatic means and to said means for effecting snap action of said valve for transmitting movement from both of said thermostatic means to said means for effecting a snap action of said valve.

2. A structure as in claim 1, wherein the means for effecting snap action of said valve includes a rigid disk and a concavo-convex snap spring element.

3. In a thermostatically operative valve structure; the combination with thermostatic means responsive to the water temperature in the container of a water heater; of safety shut-off thermostatic means for the gas burner of said water heater; a valve casing having a gas inlet and a gas outlet with a valve port between them; a single valve responsive to both said water thermostat and said safety shut-off thermostatic means for controlling said valve port; means for effecting snap action of said valve; and a conical block having the slant height surface thereof in operating relation to both of said thermostatic means and having the base of said block in operating relation to said means for effecting snap action of said valve for transmitting movement from both of said thermostatic means to said means for effecting a snap action of said valve.

4. A structure as in claim 3, wherein the means for effecting snap action of said valve includes a rigid disk and a concavo-convex snap spring element.

ROBERT J. DOUGHERTY.
